UNITED STATES PATENT OFFICE.

ARTHUR COELHO, OF BROOKLYN, NEW YORK.

ATTACHMENT TO LINOTYPE MACHINES.

Application filed September 13, 1921. Serial No. 500,313.

To all whom it may concern:

Be it known that I, ARTHUR COELHO, a citizen of Brazil, residing at Brooklyn, New York, have invented certain new and useful 5 Improvements in Attachments to Linotype Machines, of which the following is a specification.

This invention has for its object the providing, on a linotype machine, of means for 10 using matrices with two fonts of type thereon, whereby the matrices may be used to present either font of type thereon effectively for the line of type to be formed therefrom. That is, the matrices have one font 15 of type on one edge thereof and another font on the other edge. When the usual font or the font on the front edge is to be used, the matrices are used in the usual way but when the font on the other edge is to be 20 used, the matrices are reversed to present the reverse edge for the molding operation. The means include automatic reversal of the matrices when the reverse edge is to be used and after use, the matrices are automatically re- 25versed before entering the distributor box so that they may be thus distributed in their normal position. These means include control means for determining which edge of the matrices will be present for the molding 30 operation.

I have chosen the preferred embodiment of my invention for the purpose of illustrating it and making it clear but it is to be understood that this embodiment is used 35 in an illustrative sense and not a limiting one for obviously the invention is capable of many different embodiments without departing from the spirit and scope thereof.

I have illustrated the chosen embodiment 40 of my invention in the accompanying drawings in which Fig. 1 shows a side elevation of the magazine, the chutes leading from the magazine to the belt and the belt of a linotype machine. Fig. 2 is a perspective view of my gate means. Fig. 3 is a trans- 45 verse longitudinal section of the second elevator plate of a linotype machine with my invention supplied thereto. Fig. 4 is a view similar to Fig. 3 except that the space band lever is moved inwardly to an engaging 50 position. Fig. 5 is a view similar to Fig. 4 except that the slide bar carried by the plate is shown in full lines. Fig. 6 is an enlarged

sectional view taken along the line 6—6 in Fig. 4. Fig. 7 is a view taken along the 55 line 7—7 in Fig. 4. Fig. 8 is a plan view of the push rod. Fig. 9 is a view similar to Fig. 6 with the latch depressed instead of open. Fig. 10 is a perspective view of the latch. Fig. 11 is a perspective view of the 60 control rod. Fig. 12 is a detail of the manner of mounting of the control rod. Fig. 13 is a compound view showing the phases of action of the slide bar during its rotation. Fig. 14 is a perspective view of a usual 65 second elevator. Fig. 15 is a perspective view of a usual guide pole. Fig. 16 is a perspective view of the manner in which the matrix slides off from the slide bar. Fig. 17 is the side elevation of one of my 70 improved matrices. Fig. 18 is an enlarged view of detail. Fig. 19 shows diagrammatically how the second elevator carries the second elevator plate.

The linotype machine will operate in the 75 usual manner even though my invention is applied to that machine and the matrices will present their usual font of type or front edges for the molding operation so that my invention comprises the provision of means 80 capable of reversing the matrices to present their second font of type for the molding operation, that is, means for reversing the matrices during their passage to the molding position, and then the re-reversing of the 85 matrices before they are returned to the distributor box. To achieve this performance of reversing and re-reversing of the matrices, two attachments are required for the usual linotype machine which may be described 90 as follows:

The reversing apparatus is composed of a system of reversing channels —21, attached to the front plate —22, of an ordinary linotype machine and at the top of the reversing 95 channels is a gate —23, pivoted at the lower end of the magazine —24, of the linotype machine. The gate is provided with tongues —25, adapted to pass into and bridge over the usual channels —26, of the linotype machine whereby when the gate is pivotally moved to bridge over the usual channels, the matrices will pass along the tongues —25, and enter the channels —21, and in passing therethrough will be given one-half a 100 turn or reversed so that they will be de- 105

posed in reverse position on the usual belt 27, of a linotype machine located at the bottom of the front plate 22, that is, when the gate 23, is open the matrices fall down 5 the usual channels under the front plate and are deposited on the belt 27 in the usual position but when gate 23, is closed the matrices are conveyed past or over the mouth of the usual channels 26, into the 10 reversing channels 21, after which they are deposited onto the conveyor 27, in reverse position. From the conveyor 27, they are carried into molding position in the usual way.

15 The matrices are indicated by the numeral 28 and are provided with a usual font on their front edge 29, and a supplemental font on their reverse edge 30. The dotted line and curved arrow on Fig. 1 indicate how they are reversed in falling 20 down the reversing channels 21.

To attach to the usual machine these reversing channels 21, and their accessories, the upper glass part of the front plate 22, 25 of the linotype machine is removed and in its place is substituted the gate 23, or other control means for determining which set of channels the matrix will fall down, and the reversing channels 21 are secured to the front plate 22 of the machine. The reversing gate means is preferably formed with tongues 25, in such a manner that the present or existing channels 26, on the machine will serve as the 30 side walls. The lower end of the reversing channels will enter the lower end of the front plate for which that plate is cut and arranged so that there will be no opening anywhere.

40 In order to re-reverse the matrices between the time they leave the molding position and when they reach the distributor box, the following apparatus is provided: The usual second elevator 33 carries in 45 the usual manner the second elevator plate 34, and the usual slide bar 35 is pivotally depended from the second elevator plate by means of a pin 36 on the slide bar so that the slide bar may rotate with 50 the pin 36 as shown in Fig. 13 whereby after the matrices have been pushed onto the slide bar 35 the slide bar can be given a half turn during the upward travel of the second elevator. That is, the matrices and slide bar 35, are re-reversed 55 between the time they leave the molding position and the time they are ready to pass into the distributor box. That this action may be more clearly understood, reference 60 is made to a gear 37 provided with internal pawls 38, co-acting with the pin 36, so that rotation of the gear 37, in one direction will rotate the pin 36 and its slide bar, but rotation of the gear 37 in the opposite direction will be without

effect upon the pin 36 and its slide bar. Co-acting with the gear 37 is a rack bar 39, terminating in a stem 40 with the stem 40 being surrounded by spring 41, bearing against an abutment 42, on a 70 second elevator plate and pressing longitudinally against shoulders 43, on the rack bar 39. Universally mounted on a pivot 44 (by means of a ball and socket joint 45 with any friction means therebetween, such as a resilient lining 46) is the control rod 47, having a hooked end 48 and a tooth 49, with the tooth 49 adapted to be engaged by the space band lever 50, when the latter slides into proximity therewith.

75 The usual space band lever 50, is a reciprocating element and as it moves toward the second elevator plate 34, (while transferring a line of matrices from the first to the second elevator), the inclined face 51 of the space band lever 50, engages a similarly inclined portion 52 of the second elevator plate so that the space band lever 50, rides up on to and along 80 the second elevator plate as shown in Figs. 3, 4 and 5. Engagement of the inclined faces 51 and 52 (Fig. 3) causes the space band lever to ride up on to the elevator plate 34, (Fig. 5) in continued movement 85 along the elevator plate 34 and causes the front edge of the space band lever 50 to engage the tooth 49, on the control rod 47, whereupon further movement of the space band lever along the elevator plate, 90 pushes the rod 47 and the rack 39, longitudinally against the pressure of the spring 41 charging the spring so to speak, and during retraction of the rack 95 100 105 110 115 120 125 130 135 140 145 150 155 160 165 170 175 180 185 190 bar is pressed down over its other end to release the matrix. When the slide bar finishes its rotation or as the heads of the latches come under the plate. That is, 5 when the heads of the latches are under the plate as shown in Fig. 9, the matrices are unlocked in position whereas during the turning of the slide bar and when the heads of the latches are free to be pressed 10 upwardly by the spring —55, the matrices are in locked position on the slide bar.

To avoid having the slide bar turn before it is clear from transferring whereby it would cause the line of matrices to strike 15 on the travel channels or on the second elevator guide pole on the provided pin means —60 projecting from the edge of the second elevator plate for preventing rotation of the pin 36, the spring —61 associated with the 20 pin —60 keeps the pin —36 in normally rotatable position but as the elevator plate passes down and contacts with the guide pole —62, the pin —60 is pressed inwardly to prevent rotation of the pin —36 as the second elevator falls.

The control rod —47 controls the rotation of the slide bar —35, and to that end it is rotatably mounted. If the matrices are being used with the usual font, the control rod 30 —47, by means of its bent end or finger piece —48, is rotated through 90 degrees whereupon the tooth —49, of the rod is moved out of the path of the space band lever. In this position, the space band lever moves along 35 the second elevator plate at the time of transferring the line of matrices from the first to the second elevator without engaging the rod —47 so that the rack bar —39 is not moved, and the slide bar is not rotated with 40 respect to the second elevator plate which means that the matrices are not changed from their usual position during their return to the distributor box.

However, in the event the matrices have 45 been used in their reverse position to mould the second font of type, the operator rotates the control rod —47 back to the position shown in Figs. 3, 4 and 5, where its tooth —49 will be engaged by the space band lever —50, and the rod slightly raised on its universal pivot —44. Continued movement inwardly of the space band lever charges 50 the spring —41, which upon the receding of the space band lever, returns the rack bar —39, to initial position while during such return, the pin —36 and slide bar are rotated through 180 degrees and the matrices thereon are re-reversed ready for the distributor box where they will return in initial or normal position.

It will thus be seen that I have devised very simple attachments for the usual linotype machine, which, without materially disturbing any of its existing parts, will give

it the usefulness of two such machines by adding to its capacity a second font of type.

What I claim is:

1. In combination in a linotype machine, a plurality of matrices having one font of type on one edge thereof and another font 70 of type on the other edge, means having a plurality of sets of channels for rendering either font of type effective at the moulding position, a distributor box, and means for uniformly returning the matrices to the distributor box in initial standard position. 75

2. The apparatus of claim 1 in which the means for rendering either font of type effective has a plurality of sets of channel means, and a gate for directing the matrices 80 through any set of said channel means.

3. The apparatus of claim 1 in which the means for rendering either font of type effective has a plurality of sets of channel means, one of said sets having its channels 85 twisted, and a gate for directing the matrices through any set of said channel means.

4. The apparatus of claim 1, in which the means for returning the matrices has a second elevator plate, a slide bar, and selective 90 means for rotating the slide bar with respect of said plate.

5. The apparatus of claim 1, in which the means for returning the matrices has a second elevator plate, a slide bar pivotally 95 mounted on said plate, a space band lever, and selective means for permitting said space band lever to rotate said slide bar with respect of said plate.

6. The apparatus of claim 1, in which the means for returning the matrices has a second elevator plate, a slide bar, a pin pivotally securing said slide bar to said plate, a gear on said pin, reciprocating means for coacting with said gear to rotate said slide 105 bar upon said plate, a space band lever, and selective means for rendering said space band lever effective to reciprocate said reciprocating means to rotate said slide bar.

7. The apparatus of claim 1, in which the means for returning the matrices has a second elevator plate, a slide bar adapted to receive and carry the matrices, selective means for rotating the slide bar, and means for preventing matrices from falling off the 110 slide bar during its rotation.

8. The apparatus of claim 1, in which the means for returning the matrices has a second elevator plate, a slide bar adapted to receive and carry matrices, selective means 120 for rotating the slide bar, a second elevator guide pole, and means for preventing rotation of the slide bar during the time of contact of the elevator plate with the guide pole.

In testimony whereof I have affixed my signature to this specification.

ARTHUR COELHO.
